HANDED STEERING WHEEL

John T. Le Rose, 35—35 72nd St., New York, N.Y.

Filed Apr. 20, 1964, Ser. No. 79,616

Term of patent 3½ years

(Cl. D14—30)

FIG. 1

FIG. 3

FIG. 2

FIG. 1 is a top plan view of a handled steering wheel showing my new design;

FIG. 2 is a side elevational view thereof; and

FIG. 3 is a front elevational view thereof.

I claim:

The ornamental design for a handled steering wheel, substantially as shown.
